UNITED STATES PATENT OFFICE.

JAMES F. ATWOOD, OF CLAREMONT, NEW HAMPSHIRE.

GARMENT-SUPPORTING CLASP.

No. 874,820.

Specification of Letters Patent.

Patented Dec. 24, 1907.

Application filed July 10, 1907. Serial No. 383,026.

To all whom it may concern:

Be it known that I, JAMES F. ATWOOD, a citizen of the United States, residing in Claremont, in the county of Sullivan and State of

5 New Hampshire, have invented a new and useful Improvement in Garment-Supporting Clasps, of which the following is a specification.

This invention relates to clasps for supporting garments or portions thereof, such as stockings, underwear, etc., and particularly to that class of garment-supporting clasps in which two pivotally connected jaws or members which are held normally apart 10 by a spring are forced against opposite sides of the garment by means of a lever which, when the clasp is thus closed against the fabric, is locked in such closed position.

The invention consists of a certain new and 20 novel construction and arrangement of parts fully described below, and illustrated in the accompanying drawings, in which—

Figure 1 is a front elevation of my improved clasp in position on a suitable web or 25 tab which is adapted to be attached to a garment. In this figure dotted lines indicate a portion of the garment or fabric to be supported. Fig. 2 is a vertical section taken on line 2—2, Fig. 1, with the clasp in a closed 30 position and the article being supported indicated in full lines. Fig. 3 is a similar section illustrating the clasp in an open position. Fig. 4 is an inside view of the swinging or movable jaw or member. Fig. 5 is a view of 35 the lever detached. Fig. 6 is an inside view of the stationary jaw or member. Fig. 7 is a section taken on line 7—7, Fig. 6.

Similar letters of reference indicate corresponding parts.

40 The clasp comprises a stationary jaw, a swinging or movable jaw, a spring adapted to hold the movable jaw with its clamping end forward or away from the stationary jaw, and a locking lever pivotally connected with 45 the stationary jaw and extending through the movable jaw.

The stationary jaw comprises the main portion *a* of flat metal and provided with the horizontal slots *b*, *c* and *d*, said main portion 50 being preferably formed with raised edges *a'* for stiffening purposes. Near its upper end it is provided at its edges with ears *e* opposite

the ends of the slot *b*, and its central portion is formed up at *f* to receive the ends *g'* of a horizontal staple-shaped pivot-pin *g*. See 55 Figs. 6 and 7.

The swinging member or jaw comprises the flat portion *h* preferably provided with a stiffening edge *h'*, (which as the jaw *h* extends down somewhat lower than the jaw *a*, 60 is adapted to underlap the lower end of said jaw *a*), and at its upper end on opposite sides with ears *i* which are adapted to lie inside of or between the ears *e* when the two jaws are secured together by a horizontal pivot *j* 65 which extends through said ears *e* and *i*. This movable jaw is provided near its lower end with a broad horizontal slot *k*, a horizontal inwardly extending lip *k'* being formed next the lower edge of said slot. Above the 70 slot *k* is a smaller horizontal slot *l* which is provided with a shorter extension *l'* constituting a recess, and producing shoulders *m* at its opposite ends next and above the broader portion *l* of the slot. 75

A spiral spring *n* surrounds the pivot-pin *j*, and its ends *n'* force the two jaws normally apart. A lever consisting of the long arm *p* and the short arm *r* (Figs. 1, 2, 3 and 5) extends from the staple-shaped pivot *g*, to 80 which it is connected by the hooked end *r'*, through the slot *l*, said lever being provided at its outer end with a short wedging-arm *s* which extends from the upper or inner surface of the long arm *p* of the lever upward at 85 substantially an acute angle therewith, being however preferably curved as illustrated.

t represents the web to which the clasp is secured, and *u* is a portion of a fabric or garment to be supported by said clasp. The 90 web *t* is secured to the stationary jaw by friction, and when thus secured is in the position illustrated, in which it extends down in front of the upper edge of the main portion *a* of the stationary jaw, thence rearward through 95 the horizontal slot *b* behind said portion and down under the lower edge thereof and forward and up in front of the lower horizontal portion of the stiffening edge *a'*, and thence rearward through the slot *d* behind the plate 100 *a*, forward through the slot *c* and rearward through the same slot and upward behind the plate *a*, as illustrated in Figs. 2 and 3. Within the portion which extends forward

through the slot *c* a rod or pin *v* is inserted horizontally, said rod or pin being of suitable diameter to prevent the portion which extends forward in front of the slot *c* from 5 being pulled into said slot. The slot *k* in the movable jaw is sufficiently broad to accommodate this projecting portion of the web when the clasp is closed. By this means the tab is locked into engagement with the stationary jaw and effectually prevented from 10 being pulled out of engagement. Thus the web covers the back of the clasp and is interposed between it and the person when the clasp is being worn.

15 When the fabric or garment *u* is to be engaged by the clasp, it is inserted between the two members or jaws while the clasp is in the open position illustrated in Fig. 3, and then the movable jaw *h* is pressed back against 20 the fabric, the lip *k'* extending against it just under the rod *v*, and the lower horizontal portion of the stiffening edge *h'* underlapping the fabric and pressing it against the portion of the tab which extends around the horizontal portion of the stiffening edge *a'*. The 25 swinging member having been thus pressed against the fabric *u*, the lever *p*, *r* is forced upward until its long arm *p* lies flat against the outer surface of the movable jaw *h*, and 30 when being swung into such position the short arm *r* of the lever swings through the main portion of the slot *l* and enters the extension or recess *l'*, and the long arm *p*, which is a trifle wider than the short arm *i*, 35 and hence wider than the extension *l'* of the slot *l*, bears against the shoulders *m*. Moreover as the long arm is pressed into the above described position the wedging-arm *s* is forced over the upper edge of the plate *a*, 40 and the lever is thus locked firmly into position, whereby the swinging arm cannot be forced out by the spring *n*, *n'*, but must be pulled out of position by hand.

Having thus fully described my invention, 45 what I claim, and desire to secure by Letters Patent, is:—

1. In a clasp of the character described, a stationary jaw comprising a plate provided with a horizontal slot near its upper end and 50 a pair of horizontal slots near its lower end, a webbing extending rearwardly through the highest slot, around the lower edge of the stationary jaw and rearwardly through the lowest slot, and forward and back through 55 the higher of the two lower slots; a movable jaw pivotally connected with the stationary jaw and provided with an inwardly or rearwardly extending lip which when the clasp is closed is opposite the portion of the stationary jaw which is between the two lower slots, the lower ends of the two jaws being at 60 different heights and provided with inwardly bent horizontal edges one of which overlaps the other, and means for closing the jaws and

maintaining them in clamping relation for 65 the purpose set forth.

2. In a clasp of the character described, a stationary jaw comprising a plate provided with a horizontal slot near its upper end and a pair of horizontal slots near its lower end, 70 whereby the web may be applied by passing it rearwardly through the highest slot, around the lower edge of the stationary jaw and rearwardly through the lowest slot, and forward and back through the higher of the two 75 lower slots; a movable jaw pivotally connected with the stationary jaw and provided with an inwardly or rearwardly extending lip which when the clasp is closed is opposite the portion of the stationary jaw which is between the two lower slots, and with a slot adapted to accommodate the portion of the web which projects forward through and in front of the upper of the two lower slots in the stationary jaw, the lower ends of the two 85 jaws being at different heights and provided with inwardly bent horizontal edges one of which overlaps the other, and means for closing the jaws and maintaining them in a clamping position, for the purpose set forth. 90

3. In a clasp of the character described, a stationary jaw; a movable jaw pivotally connected near its upper end with the corresponding portion of the stationary jaw, and provided with a horizontal slot having an upward extension which is of less length than the main portion of the slot, whereby shoulders or ledges are produced at opposite ends of the said extension; and a locking lever consisting of a short arm pivotally connected 100 with the stationary jaw, and a long arm at substantially right angles with the short arm and extending through said slot, said long arm being broader than the length of the extension to the slot, whereby when the lever 105 is swung upward to force the movable jaw against the stationary jaw the short arm thereof is moved into said extension of the slot and the long arm bears against the shoulders or ledges at the opposite ends of 110 the said extension, for the purpose set forth.

4. In a clasp of the character described, a stationary jaw; a movable jaw pivotally connected near its upper end with the corresponding portion of the stationary jaw, and provided with a horizontal slot having an upward extension which is of less length than the main portion of the slot, whereby shoulders or ledges are produced at opposite ends of the said extension; a locking lever consisting of a short arm pivotally connected 115 with the stationary jaw, and a long arm at substantially right angles with the short arm and extending through said slot, said long arm being broader than the length of the extension to the slot, whereby when the lever 120 is swung upward to force the movable jaw against the stationary jaw the short arm 125

thereof is moved into said extension of the slot and the long arm bears against the shoulders or ledges at the opposite ends of the said extension; and a wedging-arm extending 5 from the long arm near its outer end and bearing against the upper edge of the stationary jaw when the jaws are closed, for the purpose set forth.

In testimony whereof I have signed my name to this specification in the presence of 10 two subscribing witnesses.

JAMES F. ATWOOD.
